UNITED STATES PATENT OFFICE.

EDWIN D. TEAGUE, OF BROOKLYN, NEW YORK, ASSIGNOR TO NORTH AMERICAN LACE COMPANY, OF PHILADELPHIA, PENNSYLVANIA, A CORPORATION OF PENNSYLVANIA.

DESIGN FOR LACE.

Application filed February 20, 1925. Serial No. 12,437. Term of patent 3½ years.

To all whom it may concern:

Be it known that I, EDWIN D. TEAGUE, a citizen of the United States, residing in Brooklyn, Kings County, New York, have invented a new, original, and ornamental Design for Lace, of which the following is a specification, reference being had to the accompanying drawing, forming part thereof, in which the figure is a face view of a piece of lace, illustrating my new design, partly in outline, with certain portions in full lines, which are repeated in that portion of the design shown in outline.

I claim:

The ornamental design for lace, substantially as shown.

EDWIN D. TEAGUE.
